UNITED STATES PATENT OFFICE.

DAVID JANKOWER, OF NEW YORK, N. Y.

SINGLE-COMPOUND-KEY TYPE-WRITER.

1,301,444.

Specification of Letters Patent. Patented Apr. 22, 1919.

Application filed February 14, 1918. Serial No. 217,093.

To all whom it may concern:

Be it known that I, DAVID JANKOWER, a citizen of the United States, and resident of New York city, in the county of New York and State of New York, have invented certain new and useful Improvements in Single-Compound-Key Type-Writers, of which the following is a specification.

The subject of this invention is a type-
writer that is operated in a similar manner
to that of the ordinary key-board instru-
ment; namely, by pressing the finger on any
individual visual character and thereby
printing a corresponding character on paper.

It differs from the key-board instrument
however in having only a single compound-
key instead of the many individual keys
with their connecting and operating parts
necessary in that class of typewriters.

The single key, referred to in the present
invention, consists of a circular plate uni-
versally supported and having visual char-
acters (letters of the alphabet, etc.) around
its outer edge, which characters, although
they all move when any individual one is
pressed down, do not bring their corre-
sponding printing characters in contact with
the paper—the individual character only
that is pressed upon having its correspon-
ding character printed.

The single key-plate, used in the present
case, through dispensing with the many indi-
vidually moving keys, and their multitude
of connections common to the ordinary key-
board instrument, allows of a great saving
in the cost of manufacture and a general
simplification in construction, as will be
seen by an examination of the accompan-
ying partially diagrammatic drawings, of
which:—

Figure 1, is a plan view, with central cap
removed; Fig. 2, a front vertical view, par-
tially in section, of the main parts of Fig. 1;
Fig. 3, a vertical cross-section, through dotted
line Z, Z, of Fig. 1; Fig. 4, a modification
of the universal movement shown in Fig. 1;
Fig. 5, a detail of the rod and pawl operat-
ing the paper carrier; Fig. 6, plan view of
key-plate 2, with leveling springs under-
neath. Similar numerals refer to similar
parts throughout the different views.

Referring now to Fig. 1: 2, is a key-plate,
with its central cap removed; 3, curved bar,
integral with base 1; 4, horizontal extension
of bar 3; 5, ball rigidly connected to bar 4,
and serving as a central support for the
universal movement of which key-plate 2
forms a part; 6, ring freely pivoted to ball
5; 7, pivots connecting ring 6 to ball 5; 8,
pivot pins connected to cylinder 20 and serv-
ing to pivot cylinder 20 to ring 6, the pivots
being at right angles to pivots 7; 9, points
of pins contacting with ring 6; 10, partially
punched-out section of key-plate 2, opposite
to the letter L and twisted underneath the
said key-plate 2 so as to be in a direct line
with the center of the said letter L and its
corresponding printing letter L (see 11 in
Fig. 2); 12, paper carrier; 13 teeth on
turned-up edge of paper carrier 12; 14, 70
guides for paper carrier 12; 15, shaft for
paper feed; 16, rubber rolls on said shaft;
17, bearings for shaft; 18, handle for mov-
ing paper forward; 19, rod for word spac-
ing; 21, opening in key-plate 2, through
which spacing rod 19, protrudes.

In operating the instrument, the move-
ments and combinations that take place will
now be explained.

Supposing that the letter L is the begin-
ning of a word; the finger is placed in the
saucer-shaped depression on which the let-
ter is printed and a downward pressure ex-
erted; this causes the outer edge of the key-
plate nearest to the said letter L to move in
the arc of a circle (see dotted curved line in
Fig. 2) until the lower point of the blade
10 comes into contact with the lowest part
(29) of the V-shaped slot 23 at the right
hand side of cylinder 22; the blade 10 is 90
locked at this point, as far as its curved
movement is concerned, by reason of the cyl-
inder 22 being confined to a vertical motion
by rod 19 which passes through an opening
in the bottom of frame of the said cylind-
er 22 and also through an opening in the hori-
zontal stationary bar 4 which serves to hold
it in a vertical position; with the blade 10
locked as described at point 39 (see dotted
lines for angle of blade 10 while in this posi-
tion) the printing character L (numbered
11) at the bottom of cylinder 20, in line with

the large L on the key-plate 2, has swung through the arc of a circle, the ball 5 of which is the center, to point 40 (Fig. 2) as indicated by arrow; the pressure of the finger on the letter L of key-plate 2 being continued, the cylinder 22 is forced downward against the pressure of spring 26 in socket 25 (Fig. 3) and carries with it rod 24 (to which it is permanently secured at 32), to the top of which is pivotally connected ring 6 and cylinder 20; it (cylinder 22) also carries downward spacing rod 19, by means of the bottom of said cylinder 22 coming in contact with pin 38 of said rod 19 against the light pressure of spring 35, until the pawl 30 (Figs. 3 and 5) has contacted with the teeth 13 and moved the paper carrier 12 the distance of one letter to the right; the continued pressure of the finger on letter L of key-plate 2 being maintained the printing character L (numbered 11) at the bottom of the cylinder 20 is brought into contact with the paper 33 and impressed upon the same, after which the various parts resume their normal position ready for the next letter to be printed by following the same motions as above described.

When a word has been printed, a space on the paper is left between it and the beginning of the following word by pressing down rod 19, thereby making the pawl 30 contact with teeth 13 of the paper carrier 12 and moving it one space. The opening 21 in key-plate 2 through which rod 19 passes is made large enough to clear the rod when the said key-plate is tilted out of its normal position, but when the tilting motion is stopped by the blade 10 contacting with the bottom of the V slot 23 of cylinder 22, and a downward vertical motion of the entire universal movement takes place, the rod 19 is also brought downward by the bottom of cylinder 22 pressing on pin 38 secured to the said rod 19 and thereby bringing the pawl 30 into connection with teeth 13 of the paper carrier 12.

The cylinder 20 is cut away for the purpose of allowing enough space for the interior mechanism without conflicting with the free swing of the said cylinder 20, as well as for reducing its weight.

Rod 19, which by means of the pawl 30 at its lower end, serves to give a side motion to the paper when the said pawl 30 contacts with the teeth 13 of the rear turned-up edge of the paper-carrier 12 also serves by passing through the guide opening in frame 31 of cylinder 22 to confine the said cylinder 22 to a vertical movement only.

Pivots 7 and 9, forming part of the universal movement, prevent any lateral motion of key-plate, confining it entirely to a tilting motion until the character to be printed reaches point 40 (see arrow in Fig. 2), when

the entire universal movement partakes of 75 a downward vertical motion until the type-character in position for printing has been impressed on the paper.

Normally the cylinder 20, by means of gravity, retains a vertical position and the 70 key-plate 2 a horizontal one until any part of the said key-plate 2 is moved downward after which, when the pressure of the finger is released it regains its original position. To hasten the return action, a system of 75 springs (41, in Fig. 6), may be used.

For clearness of explanation only a few V-shaped slots (23 in Fig. 2) in cylinder 22 are shown but it is understood that there is an individual V-shaped slot in the said cylinder 22 for each character on the surface of key-plate 2.

It is also understood that although only one partially punched-out blade (10, in Figs. 1 and 2) is shown on key-plate 2 that an individual one is used for each character.

These blades after being partially cut out and pressed down are turned at a right angle in a direct line with the centers of the characters on the keyboard as well as with 90 the V-shaped slots in cylinder 22 and the corresponding characters at the bottom of cylinder 20.

The universal movement, shown in Fig. 4, has an extra ring 36, and two pivots 37, and 95 may be used in place of that shown in Figs. 1, and 2, to serve in more fully equalizing the pressure exerted in printing the different characters.

Other means and other mechanism than 100 those shown, may be used for shifting the paper, and I do not claim, in this specification, any particular method for doing so.

I claim:

1. A compound-key typewriter consisting 105 of a universally supported tilting key-plate having downwardly projecting blades, the said key-plate having secured near its center a cut-away downwardly projecting cylinder with type-characters on its lower end; in 110 combination with a second cylinder, limited to vertical movements and having V-shaped punched-out slots around its circumference adapted to coöperate individually with the corresponding blades of the before mentioned key-plate; the whole in combination with a paper-shifting mechanism, and means for bringing the several movable parts to their original positions after a letter has 115 been printed.

2. A compound-key typewriter consisting 120 of a central rod carrying a cylinder with V-shaped slots around its circumference, the upper end of the said central rod being connected, through the medium of a universal 125 mechanism, with a tilting key-plate having a downwardly projecting support for type-characters and a series of downwardly pro-

jecting blades corresponding with the characters on the upper surface of the said key-
plate; a tube, connected to the base by means
of a supporting arm, in which tube the cen-
tral rod is arranged to move; the whole in
combination with paper-shifting and feed
mechanism.

Signed at New York city, in the county of
New York and State of New York, this the
13th day of February, A. D. 1918.

DAVID JANKOWER.
